DOOR HANDLE FOR A REFRIGERATOR CABINET

Paul E. Petkowitz, Detroit, Mich., assignor to General Motors Corporation, Detroit, Mich., a corporation of Delaware

Application October 30, 1956, Serial No. 43,588

Term of patent 3½ years

(Cl. D67—3)

Figure 1 is a front view of a door handle for a refrigerator cabinet embodying my new design;

Figure 2 is an enlarged top plan view of the handle shown in Figure 1;

Figure 3 is a side elevational view of said handle; and

Figure 4 is an enlarged sectional view taken on the line 4—4 of Figure 1, in the direction of the arrows.

The dotted line representations of a refrigerator or portion thereof are for illustrative purposes only.

I claim:

The ornamental design for a door handle for a refrigerator cabinet, as shown and described.
